PATENTED JUN 21 1870

United States Patent Office.

JAMES E. STRODE, OF HILLSBOROUGH, ILLINOIS.

Design No. 4,173, dated June 21, 1870.

DESIGN FOR A RING AND BUCKLE.

The Schedule referred to in these Letters Patent and making part of the same.

I, JAMES E. STRODE, of Hillsborough, Montgomery county and State of Illinois, have invented and produced a new and original Design for a Ring and Buckle combined, for halters, of which the following is a specification.

The nature of my design is fully represented in the accompanying drawing, to which reference is made.

Figure 1 is a plan view, and

Figure 2 is a perspective view of my design for a combined ring and buckle.

Claim.

I claim as my invention—
The design for ring and buckle, united, as shown.
Witnesses: JAMES E. STRODE.
